ELECTROMAGNETIC OPERATOR FOR LIGHT SIGNALS

Oscar S. Field, Rochester, N. Y., assignor to General Railway Signal Company, Rochester, N. Y.

Original application July 23, 1930, Serial No. 470,056. Divided and this application August 4, 1937, Serial No. 157,334

2 Claims. (Cl. 175—339)

This invention relates in general to light signals, and has more particular reference to a light signal wherein a single light source, in cooperation with a movable screen carrying a plurality of colored transparent members, operates to give a plurality of different signal indications.

This application is a division of my copending application Ser. No. 470,056, filed July 23, 1930, for "Light signals for railroads"; now Patent No. 2,097,785, granted November 2, 1937.

Among the objects of the present invention is to provide a light signal of the character in question which is simple in construction, cheap to manufacture, readily accessible for inspection and repair, and has a long useful life.

A further object of the present invention is to provide an improved means for inserting and fixing in place, a mechanism casing in the signal casing.

A further object is to provide a motor element having a permanent magnetic field whereby to minimize the requirement for power sources at the signal location, so that primary batteries can be readily used and thereby obviate necessity for a power line or storage batteries.

A further object of the invention comprises providing a novel friction fly wheel, carried on the shaft of the armature of the motor element, for preventing rebound when the motor moves to energized position.

A further object of the present invention is to provide a novel and improved centering means for bringing the motor element, when deenergized, to its neutral position in an accurate and certain manner.

Further objects, purposes and characteristic features will appear as the description progresses, reference being made to the accompanying drawings, showing, solely by way of example, and in no manner in a limiting sense, one form which the invention can assume. In the drawings:

Fig. 1 is a side elevational view, with parts shown in section, of a light signal in accordance with the present invention.

Fig. 2 is a sectional view, on line 2—2 of Fig. 3, viewed in the direction of the arrows.

Fig. 3 is a half sectional, half elevational, view on line 3—3 of Fig. 2, viewed in the direction of the arrows.

Fig. 4 is a sectional view on line 4—4 of Fig. 2, viewed in the direction of the arrows.

Fig. 5 is a sectional view on line 5—5 of Fig. 3, viewed in the direction of the arrows.

Fig. 6 is a fragmentary sectional view, on line 55

6—6 of Fig. 1, viewed in the direction of the arrows.

Referring now to the drawings, and first to Fig. 1, there is here shown a signal pole 1, on which is carried a cap 2, adjustable horizontally thereon and then fixable in adjusted position. The cap 2 has a transverse slot 2¹ formed therein, with lugs 2² at the inner ends of the slot, to receive shaped strap 3², having an inwardly projecting pin 4¹, against the post 1, pin 4¹ fitting into a receiving socket 4², in post 1, to thereby anchor the strap to the post, and adjustably connect the cap 2 to the anchored strap.

With this arrangement of parts, cap 2 can be readily adjusted angularly on post 1, by tightening one of the nuts 3¹, and loosening the other, to thus turn the cap on the anchored strap.

Carried by the cap 2 is a signal casing SC, pivoted as at 4 to the cap 2, and having an adjusting means, comprising a threaded stud 5 and nut 6, for tilting the casing SC in a vertical plane on its pivot point 4.

Carried within the signal casing SC is a mechanism casing MC, having a depending bracket 7, carrying a pin 8 at its lower end for engagement in an aperture 9 in a lug 10 carried by the signal casing. The signal casing has two pins 11, in its sides, for cooperation with two latches 12, pivoted at 13 to the mechanism casing, and biased by springs 14 in a counter-clockwise direction as viewed in Fig. 1, whereby to snap the catches 12 over the pins 11 and thereby hold the mechanism casing MC in position in the signal casing SC on the two horizontal pins 11 and the lower pin 8. The latches 12 have offset lugs 15 for contacting with the upper face of bracket 7 to limit the rotation due to springs 14, when the mechanism casing is removed from the signal casing.

Carried on the top of the signal casing SC, is a sighting device including an apertured member 16 and a member 17, carrying cross hairs or the like for defining a point in space, with the aperture 16 and the cross hairs defining a line in space parallel to the optical axis of the lens system in the light signal, whereby to permit readily directing the focussed signal beam to any desired point.

Carried on the front of the signal casing is an adapter 18, having at its outer end a lens 19, shown as a plano-convex lens of the condensing type, for directing light beams passing therethrough in a substantially cylindrical beam.

Carried on the adaptor 18 is a sunshade or visor 20, and carried by the signal casing is a back-

ground 21 fastened in place by screws or the like 22.

In combination with the lens 19, is an auxiliary lens 23, carried in a bracket 24 fastened to the adaptor 18.

Referring now more particularly to Fig. 2, the mechanism casing MC is here shown in section, and comprises a preferably transparent bowl 29, held by means of a strap 30 and thumb screws 31, in position against the main portion 32 of the mechanism casing.

Carried in a socket in the casing portion 32, is a light unit LU, including a light source 33, shown as an incandescent bulb adjustably carried in a mounting 34 so as to position it at one of the conjugate foci of an elliptical reflector 35, the other conjugate focus of the reflector being at the point 36, immediately to the rear of a movable spectacle 37 carrying a plurality of different colored glasses 38, as more readily seen in Fig. 4. The light unit LU can be readily slipped into place in the casing portion 32 and held therein by a bayonet joint or the like, as shown in the application of which this is a continuation. The mechanism casing is provided with a hand hole 39 for facilitating handling of the same.

In the front of the casing portion 32 is an aperture 40 for receiving a conical member 41 having longitudinal corrugations 42 covering its entire inner surface. These corrugations 42 have sharp edges, and smooth faces, whereby to cause light entering through the plano-convex lens 43, which is positioned over the outer larger opening of the cone member, to be reflected back and forth from one side of the cone to the other, if it strikes on the pointed edges of the corrugations, and if these edges are not so sharp as to substantially prevent any reflection, and to be reflected from one inner face to the other of the various corrugations if it strikes at such points. Furthermore, if the cone member 41 were to be smooth on its inner surface, then the entire surface would act to reflect light entering from the outside, back and forth across the cone as the light travels inwardly, to prevent any light so entering, from leaving the casing, without first having reached the spectacle 38, so as to largely prevent any washing out or dimming of the color of the signal glass then in controlling position. Some small portion of this light, however, would emerge from the signal, due to surface reflection from the signal glass, as uncolored light and thus produce a washing out of the color of the signal aspect then in force. The corrugations, however, as employed in this signal largely prevent this undesirable effect by largely preventing the entering light from reaching the signal glass, and also from emerging at all from the signal except in a very dispersed condition.

It will be noted that the cone member 41 has its inner open end immediately adjacent the spectacle 37, whereby any light from outside that reaches the spectacle 37 must either reach it directly and pass therethrough or else be reflected back and forth by the cone member until it is so diffused that it cannot pass out again in a manner to give a phantom indication. Were there any flat reflecting faces anywhere adjacent the focal point 36, light from the outside might reach the same and be reflected outwardly again to give a false indication, this being particularly the case if such reflecting surface were at the outer side of the spectacle. By 75

the above arrangement, little or no light from the outside can enter the casing and be reflected out again, without first passing through the spectacle 38, and due to the opening cover 43 being spaced a considerable distance from the focal point 36 and to the fact that no other surface is adjacent this focal point, any such light as does reflect out of the casing before passing through the spectacle 38, reflects from points considerably spaced from the focal point 36, and hence does not fill the opening 49 with the reflected light. Accordingly such light as thus reflects out can at most produce only bright spots at the opening or on the closure for the opening instead of covering the entire opening and thus tending to wash out or gray the color of the indication then in force.

Carried by the casing portion 32, are two spaced side brackets SB, supported by studs 90. Between these support brackets are carried two boxlike field members 44 by means of through bolts 45, with spacers 46 between the substantially parallel sides 47 of the field pieces, to permit tightening up the connection without col- lapsing the field pieces.

Carried by means of a through bolt 48, and nuts 49, is a permanent magnetic field structure including four permanent magnets in the form of four bars 50, two at each side of the bolt 48. Each pair of magnets 50, is spaced by spacers 51, with the magnetic bars and bolt 48 held together in a bundle by means of two spaced annular washers 52, passing around the same and fitting into slots 53 in the spacers 51 whereby to hold the entire permanent magnetic field structure of the motor element in proper position.

Carried on spindles 54, pivoted at 55 in knife-edge bearings, is an armature A, having an armature winding 56, on a core 57, with vanes 58 and 59 pinned to the core 57 by pins 60 and held rigidly in place by nuts 61. As can be readily seen in Fig. 2, the vanes 58 and 59 are positioned respectively below and above the axis of the core 57 whereby, when the winding 56 is energized to make the vanes respectively of positive and negative polarity, the spindle 54 will be rocked either clockwise or counter-clockwise by the attraction of the permanent magnetic field, the permanent magnetic bars 50 making one of the boxlike field members 44 positive and the other negative. By reversing the polarity on the winding 56, the polarity of the vanes 58 and 59 can be reversed and hence the direction of rotation reversed.

Carried by the vane 59 is the spectacle 37, connected thereto by suitable means, such as rivets 62, whereby the spectacle can be moved to position any one of its three colored glasses 38 in front of the focal point 36, the center glass 38 being positioned at the focal point 36 when winding 56 is deenergized, and the outer glasses 38 being so positioned when the winding 56 is energized with one or the other polarity.

Carried by the vane 58, is a counter-weight 63, for balancing the weight of the spectacle 37.

For defining the energizing positions of the vanes 58 and 59, there are provided adjustable stop screws 64 against which the vane 58 strikes when it reaches its energized position in either direction.

For accurately and positively returning the armature and its connected parts to neutral position, upon the deenergization of winding 56, there is provided a centering mechanism. Fas- tened to the vane 58, is a plate like arm 65, to the

top of which is fastened a crown 66 and to this crown 66 are pivoted two arms 67 each of which has a longitudinal slot 68 in its lower end for receiving a pin 69 carried in the bifurcated end 70 of a centering weight 71 which is pivoted at 5 72. Each centering weight normally rests on an adjustable stop screw 73, when the parts are in neutral position.

With the structure above described, on the armature A moving to an energized position, as 10 for example, clockwise, as viewed in Fig. 4, the left hand arm 67 is raised to thereby raise centering weight 71, whereby, upon the armature being deenergized, the centering weight moves the parts back to neutral position. At the same 15 time the right hand arm 67 is permitted to move downwardly due to its slot 68, while the right hand centering weight 71 remains in its neutral position, resting on the screw stop 73.

Carried by one of the centering weights 71, are 20 movable contacts 74, which cooperate with fixed contacts 75 and 76 carried on an insulating bar 77 bolted, as by means 78, to the boxlike field members 44.

When the armature winding 56 is energized, 25 and the vanes 58 and 59 are moved to energized position to cause vane 58 to strike against one of the stop screws 64, there is a tendency for the parts to rebound from the stop screws before finally coming to rest thereagainst. This tendency to rebound is very effectually prevented by means of a friction fly wheel FF, loosely carried on one of the spindles 54, with a spring 79 sleeved between the friction fly wheel and a collar 80 pinned to the spindle 54, whereby to bias the fly 30 wheel inwardly to compress friction discs 81 positioned between the fly wheel and a shoulder 82 on the core 51.

With the arrangement of parts just described, when the armature is moved to energized position, the friction fly wheel FF continues to rotate after the vanes have been brought to a stop, by rotating on the spindle 54, to thereby absorb the kinetic energy of the parts and prevent the rebound by attempting to carry the rotation beyond the position of the screw stop 64.

By employing condensing lenses to thereby utilize the light flux to the greatest advantage, it is possible to use a relatively low powered light source 33. By being enabled to use a low powered 35 50

light source, and by also employing a permanent magnetic field structure for the motor element, the total amount of energy required to operate the light signal is cut down to such a small value that primary batteries can be depended on for operating the signal and thus obviate necessity for a power line or storage battery at outlying points where the signals are located. The only power required at the signal location is that required for energizing the armature A, and the low powered light source 33.

A satisfactory indication has been obtained, under bright daylight conditions, at distances of 3500 to 4500 feet, with a light source constituted by a three watt, four volt, incandescent bulb. Thus it can be seen that the condensing lens optical system, together with a permanent magnetic field structure for the motor element, produces a combination which permits the use of primary energy sources for operation of outlying signals.

The above rather specific description of one form of the present invention, is given solely by way of illustration, and is not intended, in any manner whatsoever, in a limiting sense. Obviously, the invention can assume many different physical forms, and is susceptible of numerous modifications, and all such forms and modifications, as come within the appended claims, are intended to be covered by this application.

Having described my invention, I now claim:

1. In a light signal, a motor element including, spaced, boxlike, field pieces, a plurality of permanent magnetic bars clamped between the field pieces, spacers between the magnetic bars, and straps around the bars and held in place by slots in the spacers.

2. An electro-responsive device comprising, a field structure consisting of permanently magnetized bars having their like poles connected by magnetizable backstraps, a first and a second pair of pole pieces attached to said backstraps in such manner that the two pole pieces of each pair are of opposite polarity, the pole pieces of each pair being formed with pole faces which are located in substantially the same vertical plane, a rotor including two armatures interconnected by a magnetizable core, each armature being separated from the pole pieces of an associated pair of pole pieces by substantially vertical air gaps.

OSCAR S. FIELD.
